EXPANSION JOINT

Filed June 20, 1927

Wm F. Kleeman Inventor

By his Attorney

Geo. W. Mills Jr.

UNITED STATES PATENT OFFICE

WILLIAM F. KLEEMAN, OF CINCINNATI, OHIO, ASSIGNOR TO THE PHILIP CAREY MANUFACTURING COMPANY, A CORPORATION OF OHIO

EXPANSION JOINT

Application filed June 20, 1927. Serial No. 200,000.

My invention relates to improvement in expansion or contraction joint fillers, particularly for use in highway or other construction where it is desirable not only to provide means for permitting expansion and contraction for the adjacent construction, frequently concrete blocks, but also to provide means whereby the adjacent construction or blocks may be interlocked with each other.

10 My improved expansion joint comprises a body of material, preferably a plastic body containing a suitable filler and a reinforcement, so arranged as to retain the tongue and groove construction under the conditions 15 which it meets in handling and transportation from the factory to the place of installation, and also of such a character that it will retain the form so that it may be used as a form in the laying of the adjacent blocks, 20 especially of concrete, to give the tongue and groove form to the adjacent blocks as the concrete sets.

In the drawings, Fig. 1 is a cross section of my expansion joint filler, Fig. 2 is a cross section of the modification, and Figs. 3 and 4 are cross sections of modifications.

In the drawings, A is a body of bituminous material; BB are layers of saturated felt or similar material. In Fig. 1, A is a layer or 30 sheet of bituminous saturated felt embedded in the joint between two bodies AA of asphalt or other bituminous material. In Fig. 2, CC are two layers of similar bituminous saturated felt arranged intermediate two 35 bodies of asphalt AA and having between them an adhesive coat A 1 of asphalt or other suitable material. The sheet or layers C of bituminous saturated felt serve as reinforcements for my improved tongue and groove 40 expansion joint, and if desired the outer plies BB may be dispensed with and only the intermediate reinforcement C be used. E is a tongue projecting from one side of the joint and F is a groove preferably in register with 45 the tongue. The bottom of the groove F preferably should be arranged beyond the vertical line of the opposite side of that portion of the expansion joint above and below the tongue and groove. In Fig. 3, I provide 50 a reinforcement D of metal or similar ma-

terial which may be in the form of sheet metal or expanded metal, or foraminous metal which does not extend to the top of the joint. In Fig. 4 I have shown a modification in which the felt reinforcement C is arranged between the two bodies of asphalt material. On the surface of this modification, I provide a rough or uneven surface by placing an inadhesive contact with the surface granular minerals, such as small stones, 60 coarse sand or other suitable granular material that will tend to engage with the concrete when it sets and becomes a part of it. This granular surfacing material may be placed as shown in Fig. 4 on the sides of the 65 asphalt bodies AA or may, if desired, be applied to the felt sheets BB and held in adhesive contact therewith by asphalt or other suitable material.

Claims:

1. In an expansion joint composed of a body of bituminous material, means intermediate the surfaces of said body for reenforcing same composed of a plurality of layers of bituminous saturated felt separated 75 from, but in adhesive contact with, each other, said joint being deformed longitudinally to provide a projecting tongue on one surface and a corresponding groove on the opposite surface.

2. An expansion joint having a projecting tongue on one side and a corresponding groove on the opposite side, said joint composed of a body of bituminous material, reenforcing means composed of a plurality of 85 sheets of bituminous saturated felt in adhesive contact with each other embedded in said bituminous material so as to provide a substantial body of bituminous material on each side of the reinforcement throughout 90 the tongue and groove section.

In testimony whereof, I have signed my name to this specification.

WM. F. KLEEMAN. 95
